UNITED STATES PATENT OFFICE.

JOHN F. CARR, OF CAMDEN, NEW JERSEY.

GAS-LIGHTER.

SPECIFICATION forming part of Letters Patent No. 280,573, dated July 3, 1883.

Application filed April 13, 1883. (No model.)

To all whom it may concern:

Be it known that I, JOHN F. CARR, a citizen of the United States, residing in Camden, Camden county, New Jersey, have invented 5 certain Improvements in Gas-Lighters, of which the following is a specification.

My invention consists of a gas-lighter in which a lamp is so combined with a casing that the latter shall inclose the flame, and 10 thereby prevent its contact with combustible materials.

In the accompanying drawings, Figure 1 is a vertical section of my improved gas-lighter; Fig. 2, a transverse section on the line 1 2 of 15 Fig. 1; Fig. 3, a transverse section on the line 3 4 of Fig. 1; and Fig. 4, a view drawn to a reduced scale, showing the manner of using the gas-lighter.

A wooden handle, A, of suitable shape and 20 length, is fitted and secured to a socket, a, at the lower end of a lamp, B, provided with a screw-cap, b, through a tube on which passes the wick d.

To the upper portion of the lamp is detachably fitted the lower portion or sleeve, e, of a 25 casing, D, within which is the combustion-chamber D', the casing having an enlargement, f, perforated with a number of holes, h, on the under side. Any desired number of 30 outlets, i, near the upper end of the casing permits the escape of the products of combustion from the chamber D', openings m in the casing near the upper end of the lamp admitting air for supporting combustion.

To the top of the casing is secured a slotted 35 projection, n, so that the lighter may be used as a wrench for opening and closing the valve-cocks of gas-burners.

It is important that the openings m and h 40 should be in such positions or of such a character as to direct the currents of air upward through the combustion-chamber D', as indicated by the arrows in Fig. 1, so long as the top of the lighter is held above the level of the wick-tube; but when the lighter is held horizontally, or with the upper end of the combustion-chamber somewhat below the level of the wick, air-currents will not enter through the openings m and h, and the lighter can in 45 this way be readily extinguished. If horizon-

tal openings were made in the vertical walls of the combustion-chamber, cross-currents of air created as the lighter was carried about in the hand would extinguish the light; but by making the openings h and m vertical, or in 55 some cases they would be made at an angle, in respect to a vertical line through the casing D, all currents are directed upward through the combustion-chamber at the moment they enter, and when the instrument, with the lamp 60 lighted, is held nearly vertically over a gas-burner or in the position shown in Fig. 4, the gas from the burner, whose cock has been opened, will pass with the air-currents through the openings h m, and will at once be ignited. 65

I form in the sleeve e a vertical slot, e', Figs. 1 and 4, in order to allow of the admittance of air to the flame while the casing D is being pushed down onto the lamp after the lamp has been lighted. 70

In order to prevent the casing from turning on the lamp when the instrument is used as a wrench, there is a slot in the sleeve e, which forms the lower portion of the said casing, for receiving a pin, x, projecting from the lamp. 75

Disclaiming the combination, in a gas-lighter, of a handle, lamp, and casing, I claim as my invention—

1. The combination of a lamp, B, constructed for attachment to a handle, A, with a casing, 80 D, detachably fitted to the lamp and provided with openings, all substantially as set forth.

2. A portable gas-lighter, consisting of a handle and lamp, with a casing fitted to the lamp, and having perforations vertical or at an 85 angle in respect to a vertical line through said casing, as and for the purpose set forth.

3. The combination of the lamp B, constructed for attachment to a handle, A, the casing D, having openings m and i, and an enlargement, f, perforated on the under side, 90 substantially as set forth.

In testimony whereof I have signed my name to this specification in the presence of two subscribing witnesses.

JOHN F. CARR.
